UNITED STATES PATENT OFFICE.

ARTHUR NEAL KERR, OF PITTSBURGH, PENNSYLVANIA, ASSIGNOR, BY MESNE ASSIGNMENTS, TO TRANSCONTINENTAL OIL COMPANY, OF PITTSBURGH, PENNSYLVANIA, A CORPORATION OF DELAWARE.

CYLINDER-CAR.

1,385,836.

Specification of Letters Patent. Patented July 26, 1921.

Application filed June 11, 1917. Serial No. 174,041.

To all whom it may concern:

Be it known that I, ARTHUR NEAL KERR, a resident of Pittsburgh, in the county of Allegheny and State of Pennsylvania, have 5 invented a new and useful Improvement in Cylinder-Cars, of which the following is a specification.

The invention relates to cylinder cars and more particularly to cylinder cars for transporting liquids having high vapor tension. 10

The demand for gasolene has resulted in the production of very light gasolene called casing head gasolene or naphthas which are condensed from natural gas. Some of these 15 casing head gasolenes or naphthas and particularly the lighter portions revaporated from the casing head gasolene after it is made, have a very high vapor tension and pressure is necessary to maintain the vapor 20 in liquid form. It is estimated that from one-third to one-half of the liquefied vapor made at casing head gasolene plants re-vaporizes and returns to gaseous form.

The ordinary tank car used for transporting liquids is unsuitable for transporting these high vapor tension liquids, and is, in fact, unsafe and its use is not allowed. It has therefore been necessary to devise special 25 means for transporting these "wild" or high vapor tension gasolenes and to this end the present invention has been devised.

The general object of the invention is to provide a car in which liquids having a high vapor tension may be safely transported.

Another object is to provide a doubly safe container for shipping fresh, "wild," or high vapor tension casing head gasolene or liquefied vapor which has evaporated from casing head gasolene and been condensed and reliquefied one or more times.

Another object is to provide a suitable car in which either small or large quantities of liquid having high vapor tension may 45 be safely transported.

Other objects and advantages of the invention will appear from the following specification.

An embodiment of the invention is illustrated in the accompanying drawings in which Figure 1 is a side elevation of the car with a portion of the shell broken away to show the interior; Fig. 2 is in part an end elevation and in part a transverse section

through the tank; Fig. 3 is a detail sectional view showing the filling head of one of the units; and Fig. 4 is a sectional view showing the manner of connecting one of the units to a supporting member.

The car comprises an exterior shell or 60 casing 1 preferably of cylindrical shape and formed of sheet metal and having its ends closed by the heads 5 and 6, the latter containing a plurality of openings 7 which are tightly closed by manhole covers 8. The 65 shell is provided with the usual extension 9 on its top in which is located a standard manhole opening normally closed by a cover 10. A suitable safety valve 11 is connected with the extension 9 for relieving pressure within the tank when it exceeds the usual amount. The shell is also provided with the usual valve-controlled drainage opening or leg 13 through which liquid can be withdrawn. This shell forms a liquid and 70 gas-tight container.

Within the shell and suitably secured thereto, such as by riveting, welding, or otherwise, are two or more diaphragms or auxiliary heads, each provided with a plurality of openings 14 in which are held a series of liquid containing units 2, each having one of its ends provided with filling valves accessible through one of the openings 7 in the head of the shell. The openings 14 are so spaced in the diaphragms 4 that the units 2 are efficiently distributed throughout the interior of the shell.

The tubular units 2 are preferably of cylindrical shape and made of steel of sufficient strength to withstand considerable pressure. They are built to meet the requirements of the Bureau of Explosives and may either be of seamless tubing or of other tubing with heads welded in place, according to the requirements. Each unit has riveted, welded or otherwise fastened thereto a pair of lugs 15 shown in detail in Fig. 4, the bent-up portions of which have openings registering with openings in the auxiliary head 4. The lugs are fastened to the auxiliary head by means of bolts passing through the openings. Any other suitable fastening means may be employed for securely holding the tubular units within the auxiliary 95 heads to prevent longitudinal movement of such units.

Each tubular unit is closed by a head 16

which is preferably welded in position, as illustrated more particularly in Fig. 3. The ends of the units adjacent the end of the shell having openings in it, are provided with two valves 17 and 18 by means of which the tubes may be filled and emptied. These valves may be of any suitable type, those illustrated being of the type known as Mueller valves. For the purpose of protecting these valves, the heads 16 are positioned within the ends of the tubes so that the valves are housed within the tube and do not project beyond it. There is thus no danger of breaking, bending or otherwise damaging the valves in the handling of the tubes or in case the tubes break down under end shocks on the car. Two valves are employed so that the tubes may be conveniently filled by attaching a flexible pipe from a liquid supply to one end of them, and opening the other to permit the escape of air from the tube, and also so that they may be conveniently emptied by attaching a source of pressure to the upper valve and forcing the liquid out through the lower valve.

The car may be readily manufactured and assembled by forming the metal shell in the usual manner and mounting the auxiliary heads therein. The tubular units may be manufactured in uniform sizes and then inserted in the shell and fixed in the auxiliary heads. The capacity of any tank car may be varied by varying the number of units within it, and cars of large or small capacity may be built without requiring any variation in the structure of the tubular units. The importance of this flexibility, from a manufacturing standpoint, will be readily appreciated. The construction is equally as important for purposes of repair, because any one of the units may be removed and quickly replaced by another and then repaired at leisure without interfering with the use of the car. It is very rare that more than one unit is out of repair at one time, and in case the car is not near a supply of units, such unit can be removed without seriously lessening the usefulness of the car as a whole. In other words, the structure cannot only be inexpensively manufactured by reason of the standardization of the units and the possibility of variation in tank capacities by a simple variation in the number of units, but also it is such that a continuous usefulness of the car is insured. Damage to one of the units does not materially decrease the usefulness of the car even if repair pairs to that unit cannot be immediately made.

Furthermore, the structure possesses the advantage that it is doubly safe for transporting liquids of high vapor tension. Each of the tubular units by reason of its limited

capacity can be made sufficiently strong to hold the liquid safely under pressure during transportation. If, for any cause, one of these tubular units should become damaged, the leakage of the liquid therefrom would nevertheless not endanger the car because the liquid and vapor would be held safely within the outer shell and if the pressure became excessive, such pressure would be vented through the relief valve. On the other hand, if these tubular units were shipped in a box car and one of them should leak, the vapor which is heavier than air would roll out from the box car at the level of the floor, which is about the same height from the ground as the switch lights in a railway switch yard. There would be, therefore, great danger of the whole box car becoming ignited and the other tubes exploded. With the present invention, however, if one of the tubes should leak, the liquid and vapor are retained within the shell, and under ordinary conditions would not leak outside of it. If the pressure should become excessive, the vapor would be vented through the relief valve on the top of the shell and it would become scattered before reaching the switch lights in the switch yard. If the vapor should become ignited, it would burn at the top of the metal shell instead of at the bottom of a box car as would be the case if the tubes were transported in such a car.

It is to be understood that the structure shown is for purposes of illustration only, and that variations may be made therein which come within the spirit and scope of the appended claims.

What I claim is:—

1. A vehicle body for transporting liquids having a high vapor tension, comprising a tightly closed metal shell having at its end apertures provided with closures, frames within said shell, tubular liquid-containing units supported by said frames and entirely inclosed by said shell, and filling connections to said units accessible from the outside of said shell through said apertures when said closures are removed, said units being detachable from said frames and separately removable from the vehicle body through said apertures.

2. A vehicle body for transporting liquids having a high vapor tension, comprising a tightly closed metal shell having at its end apertures provided with closures, tubular liquid-containing units supported horizontally in said shell and entirely inclosed thereby and provided with filling openings accessible from the outside of the shell through said apertures when said closures are removed, and a safety valve connected to said shell at the upper portion thereof.

3. A vehicle body for transporting liquids having a high vapor tension, comprising a

horizontal tubular metal shell, heads tightly closing the ends of said shell, vertical frames within said shell, liquid-containing tubes mounted in said frames and attached to one 5 of them and provided at one end with filling connections, one of the heads of said shell being provided with apertures adjacent to the filling connections of the liquid-containing tubes and closures for tightly closing 10 said apertures, said filling connections

being accessible from the outside of said shell through said apertures when said closures are removed.

In testimony whereof I have hereunto set my hand.
